United States Patent Office

Des. 179,868
Patented Mar. 12, 1957

179,868

TELEVISION STAND

George Trautvetter, Jenkintown, Pa., assignor to Heintz Manufacturing Company, Philadelphia, Pa., a corporation of Pennsylvania

Application October 22, 1954, Serial No. 32,769

Term of patent 14 years

(Cl. D33—14)

Fig. 1 is a perspective view of the television stand.

Fig. 2 is a side elevation.

Fig. 3 is a side elevation of a leg.

Fig. 4 is a side elevation of a leg at right angles to Fig. 3.

Fig. 5 is a bottom plan view of a leg.

Fig. 6 is a sectional view of a leg.

The dominant features of the design reside in the portions shown in the full lines.

I claim:

The ornamental design for a television stand, as shown and described.
